Des. 227,305
Patented June 12, 1973

227,305

CHEMICAL CONTAINER FOR PHOTOGRAPHIC PROCESSING

George A. Wilke, Rochester, N.Y., assignor to Eastman
Kodak Company, Rochester, N.Y.

Filed May 20, 1971, Ser. No. 145,604

Term of patent 14 years

Int. Cl. D16—04; D9—99
U.S. Cl. D61—1

FIG. 1

FIG. 2

FIG. 3

FIG. 4

FIG. 5

FIG. 1 is a top plan view of a chemical container for photographic processing showing my new design;

FIG. 2 is a side elevational view of said container;

FIG. 3 is an end elevational view of said container as viewed from the left in FIG. 2;

FIG. 4 is a bottom plan view of said container; and

FIG. 5 is an end elevational view of said container as viewed from the right in FIG. 2.

I claim:

The ornamental design for a chemical container for photographic processing, as shown.
